(57) **CLAIM**

The ornamental design for a beverage drinking apparatus, as shown and described.

DESCRIPTION

FIG. 1 is a front perspective view of an embodiment of the beverage drinking apparatus embodying my new design; FIG. 2 is a front view of the beverage drinking apparatus of FIG. 1;

FIG. 3 is a rear view of the beverage drinking apparatus of FIG. 1;

FIG. 4 is a side view of the beverage drinking apparatus of FIG. 1;

FIG. 5 is a top view of the beverage drinking apparatus of FIG. 1; and,

FIG. 6 is a bottom view of the beverage drinking apparatus of FIG. 1.

The portions of the beverage drinking apparatus shown in broken lines are included for environmental purposes only and form no part of the claimed design.

1 Claim, 6 Drawing Sheets
